(57) **CLAIM**

The ornamental design for a pet light head and accessory kit as shown and described.

DESCRIPTION

FIG. 1 is a perspective view of a light head of a pet light head and accessory kit shown separately for clarity of illustration; FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view of a bandage of the pet light head and accessory kit showing my new design;

FIG. 9 is a perspective view of a band of a pet light head and accessory kit shown separately for clarity of illustration;

FIG. 10 is another perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof;

FIG. 16 is a bottom view thereof;

FIG. 17 is a perspective view of a light head and band of a pet light head and accessory kit, shown in an assembled position;

FIG. 18 is a perspective view of a clip of a pet light head and accessory kit shown separately for clarity of illustration;

FIG. 19 is another perspective view thereof;

FIG. 20 is a front view thereof;

FIG. 21 is a rear view thereof;

FIG. 22 is a left side view thereof;

FIG. 23 is a right side view thereof;

FIG. 24 is a top view thereof;

FIG. 25 is a bottom view thereof;

FIG. 26 is a perspective view of a light head and clip of a pet light head and accessory kit, shown in an assembled position;

FIG. 27 is a perspective view of a light head, band, and clip of a pet light head and accessory kit shown in a disassembled position; and,

(Continued)

FIG. 28 is another perspective view of a light head, band, and clip of a pet light head and accessory kit, shown in a disassembled position.
